GAS ANCHOR

John M. Courtney, Atlanta, Tex.

Application June 2, 1947, Serial No. 751,901

2 Claims. (Cl. 103—220)

1

This invention relates to an improved gas anchor for use in oil well pumping mechanism and represents an improvement over the gas anchor disclosed and claimed in U. S. Letters Patent 2,291,378 granted to me on July 28, 1942.

A gas anchor is a structure affixed to the tubing string of an oil well for effecting or aiding in the separation of oil and free gas in order to protect the associated pumping mechanism from gas locks and to insure the pumping efficiency. Additionally, the gas anchor of the present invention eliminates solid material, such as sand, and thus reduces wear on the pump parts that would otherwise be caused by such solid material.

The gas anchor of the present invention has the advantage of allowing the ready escape of separated gas independent of the rate of oil inflow through the slots provided for such flow in the outer tubing of the anchor. This is particularly beneficial where, as is frequently the case, a portion of the slots become plugged with sediment. Additionally the gas anchor of the invention is, because of its special construction, readily removable from the tubing string so that access may be had to it and associated pump parts for repairs and so that the equipment may be readily salvaged in case of abandonment of the well on which such equipment is installed.

My invention may be best understood by reference to the accompanying drawing in which

Figure 1 is a vertical view, partly in plan and partly in section, illustrating the preferred embodiment of the device of this invention;

Figure 2 is an enlarged vertical section of the bottom head of the gas anchor showing in detail the construction of the ports for the flow of oil from the gas-oil separation chamber to the inlet of the tubing string;

Figure 3 is a horizontal view taken along line 3—3 of Figure 2;

Figure 4 is a vertical end view, shown in section, of one of the two hemicylindrical members which form the top head of the gas anchor; and

Figure 5 is a horizontal view taken along line 5—5 of Figure 4, showing both hemicylindrical members in their assembled position.

Referring to the drawings, 10 represents a conventional section of tubing provided with the threaded upset end 12. At the lower end of the tubing, the seating coupling 14 is threaded on to the end 12, and serves as a seat for the hold-down shoe 15 to which is attached the hollow plunger 16 provided with standing valve 18 at its upper end. The traveling tube 20,

provided with the traveling or discharge valve 22, is reciprocated over the plunger or liner 16 by a sucker rod 24, causing the oil to flow outwardly into the tubing whence it flows upwardly to be discharged at the surface.

To the bottom end of seating coupling 14 is threaded the bottom head 30, shown in detail in Figures 2 and 3, of the gas anchor. The bottom head of the gas anchor is internally and externally threaded at its upper end, for attachment to the seating coupling and for connection to the pipe barrel or tubing 32 of the gas anchor. The internal diameter of barrel 32 is larger than the tubing or the seating coupling and the annular space 34 therebetween serves as the separation zone for the gas and oil. The lower end of the head 30 is internally threaded for the receipt of sand trap 36. Oil ports 38 provide communication through the upper end of the head 30 between separation zone 34 and oil chamber 40. From chamber 40, oil flows upwardly into the stationary plunger 16 to the standing valve of the pump while sand or other solid sediment settles out into the sand trap. The oil ports 38 are internally threaded and one or more of the ports may be shut off if desired by the insertion of suitable externally threaded plugs (not shown). The side wall of barrel 32 is provided with suitable vertical slots 41 for the inflow of fluid from the producing formation.

The upper end of the barrel 32 of the gas anchor is connected to and held properly spaced from the tubing 10 by the top head 42. This head, shown in detail in Figures 4 and 5 has the general configuration of a hollow cylinder whose internal diameter corresponds to the outer diameter of the tubing. The head 42 is split to form two hemicylindrical members 44 and 46. The composite member 42 is exteriorly threaded at its lower end to fit the corresponding interiorly threaded upper end of barrel 32. Matched holes 48 are drilled into the meeting faces of each hemicylindrical member for the reception of dowel pins 50 so that the threads of each portion will be properly aligned for assembly. A plurality of grooves 52 are cut lengthwise in the internal wall of the head 42 to serve to permit the escape of gas from the separation chamber 34.

In operation the formation fluids flow through slots 41 into the barrel of the gas anchor. In zone 34 the free gas largely separates from the oil and escapes partly through the upper slots 41 and the remainder through grooves 52 in the

upper gas anchor head. Should the rate of fluid inflow be sufficient to utilize all of the free space in slots 41, the separated gas may all escape through the grooves 52. The oil and any solid sediment flows down through ports 38 into chamber 40, where the sediment largely falls out into sand trap 36. The oil then passes into the pump for passage to the surface in the usual manner.

When it is desired to remove the gas anchor the upper head 42 may be unscrewed from the barrel, split apart and removed from the tubing. The bottom head 30 may then be unscrewed from the seating coupling and the tubing and pump pulled out of the anchor.

It is to be understood that numerous modifications of the design illustrated may be made within the skill of those familiar with the art without departing from the spirit of this invention. The gas anchor is not limited in its application to any particular type of subsurface pumping equipment. The actual dimensions of the various parts, slots, grooves and ports for the passage of the fluids is dependent upon the particular pumping job and readily determinable by those skilled in the art.

I claim:

1. In a gas separator assembly, a pump tube, a reciprocating pump disposed substantially at the lower end thereof, a settling chamber disposed below said pump tube and in unrestricted communication therewith, a cylindrical surge chamber having a threaded upper end surrounding said pump tube, a series of vertically elongated openings in the outer wall of said surge chamber for the admission of oil and the escape of gas, said openings being positioned sufficiently below the top of said surge chamber so that a quantity of gas will be trapped in the chamber above the openings to make the chamber function as a surge chamber, means establishing restricted communication between the bottom of said surge chamber and said settling chamber, the improvement that comprises a cap for the upper open end of said surge chamber comprising a matched pair of hemicylindrical members adapted to fit around the pump tubing, each of said hemicylindrical members being threaded at one end, matched openings in each of said hemicylindrical members for the reception of pins to hold the threads of the hemicylindrical members in alignment so

that the cap may be fitted about the pump tubing and threaded to the threaded end of the surge chamber, whereby the upper end of the surge chamber is held in longitudinal alignment with the pump tubing, and at least one passageway through said cap for the escape of gas from the annular space between the tubing and the barrel.

2. In a gas separator assembly, a pump tube, a reciprocating pump disposed substantially at the lower end thereof, a settling chamber disposed below said pump tube and in unrestricted communication therewith, a cylindrical surge chamber having a threaded upper end surrounding said pump tube, a series of vertically elongated openings in the outer wall of the said surge chamber for the admission of oil and the escape of gas, said openings being positioned sufficiently below the top of said surge chamber so that a quantity of gas will be trapped in the chamber above the openings to make the chamber function as a surge chamber, means establishing restricted communication between the bottom of said surge chamber and said settling chamber, the improvement that comprises a tubular cylindrical cap for the open end of said surge chamber having an internal diameter slightly larger than the external diameter of the pump tubing and provided with threads at one end adapted to fit the threads on the upper end of the surge chamber whereby the surge chamber may be held in longitudinal alignment with the tubing with an axial space therebetween, said cap comprising a plurality of laterally separable segments, means for holding said separable segments in longitudinal alignment, and at least one passage through said cap for the escape of gas from the annular space between the pump tubing and the surge chamber.

JOHN M. COURTNEY.
